UNITED STATES PATENT OFFICE

164,238

TOP FOR VEHICLE BODY

Harold W. Hill, Columbus, Ga.

Application February 7, 1949, Serial No. 717

Term of patent 3½ years

(Cl. D14—28)

To all whom it may concern:

Be it known that I, Harold W. Hill, a citizen of the United States, residing at Columbus, in the county of Muscogee and State of Georgia, have invented a new, original, and ornamental Design for Top for Vehicle Body, of which the following is a specification, reference being had to the accompanying drawing, forming part thereof, wherein:

Fig. 1 is a perspective view of a top for vehicle body according to the present invention,

Fig. 2 is a similar view taken from the rear and the opposite side of the same, and

Figure 3 is a side elevational view thereof.

The dotted line showing in Fig. 3 is for illustrative purposes only.

I claim:

The ornamental design for a top for vehicle body, as shown and described.

HAROLD W. HILL.
